DESIGN FOR A DEMOUNTABLE KEY GUARD FOR A SAXOPHONE

Earl J. Gillespie, Elkhart, Ind., assignor to The Martin Band Instrument Company, Elkhart,
Ind., a corporation of Indiana

Application February 23, 1945, Serial No. 118,101

Term of patent 14 years

(Cl. D56—1)

To all whom it may concern:

Be it known that I, Earl J. Gillespie, a citizen of the United States, residing at Elkhart, in the county of Elkhart and State of Indiana, have invented a new, original, and ornamental Design for a Demountable Key Guard for a Saxophone, of which the following is a specification, reference being had to the accompanying drawing, forming a part thereof.

In the drawing:

my new design, with the bell of the saxophone and a part of the tubular body shown in dotted lines for illustrative purposes only;

I claim:

The ornamental design for a demountable key guard for a saxophone, substantially as shown and described.

EARL J. GILLESPIE.
